Gifford, Buell & Scull

ATTORNEYS

UNITED STATES PATENT OFFICE.

WILLIAM JOHN KNOX, OF NEW YORK, N. Y., ASSIGNOR, BY MESNE ASSIGNMENTS, TO
PETROLEUM CONVERSION CORPORATION, A CORPORATION OF DELAWARE.

METHOD AND APPARATUS FOR TREATING COMPOUNDS PREFERABLY OF A HYDRO-CARBON NATURE.

Application filed September 9, 1922, Serial No. 587,191, and in Canada August 24, 1922. Renewed
April 16, 1929.

My invention relates to a new and useful method and apparatus for treating compounds preferably of a hydrocarbon nature, in order to produce therefrom, or to recover 5 therefrom, constituents having commercial use or application, and the invention particularly contemplates the treatment or conversion of hydrocarbons to form other desired hydrocarbon combinations or com- 10 pounds.

My invention is an improvement over that disclosed in my co-pending application filed March 24, 1919, Serial No. 284,818, now Patent No. 1,428,641, issued September 12, 1922. 15 In this patent a process of cracking or converting oils was disclosed in which the oil to be cracked was fed as liquid to a container constituting a reaction chamber, and the heat for cracking such oil was furnished by 20 means of a heated gas, of hydrocarbon origin, which was introduced into such chamber. In contradistinction to such process, the present invention contemplates introducing into the reaction chamber, separately 25 from any liquid oil which is introduced, quantities of oil vapors which when condensed are too heavy to be suitable as motor fuels. These vapors, which in the preferred embodiment may previously have been heated 30 to incipient cracking, are physically contacted with the heated gas which performs the function of a heat-carrier, and are thereby cracked, it having been found that such conditions are favorable to the production 35 of a motor fuel of a high value. A further feature of the invention consists in causing any oil, introduced into the reaction chamber as liquid, to flow in thin films over greatly extended surfaces, thus facilitating 40 the heating and vaporizing thereof by contact with the heat-carrier gas.

A further and important feature of the invention resides in the manner of heating the carrier gas by regenerative heating 45 means, which in the disclosed embodiment consists of a brick-filled hot blast stove, similar to that used in iron smelting, containing a multiplicity of flues. To the best of my knowledge this is distinctly new to the art. By this means, large quantities of 50 heat are stored with high efficiency by burn-

ing liquid or gaseous fuel and this heat is subsequently transmitted to the heat-carrier hydrocarbon gases and vapors over a considerable period of time in a steady, uniform manner and carried into direct contact with large surfaces of preheated oil and hot vapors. 55

Other objects of my invention will appear in the specification and will be particularly 60 pointed out in the claims.

In the accompanying drawings to be taken as a part of this specification, I have fully and clearly illustrated an apparatus which is constructed in accordance with my invention, and which is particularly adapted for carrying out my improved process, but I desire it understood that my invention is not limited to the apparatus illustrated, as the same may be carried out by other apparatus, 65 without departing from the spirit and scope 70 of my invention.

In the drawings, Figure 1 is a partial diagrammatic view, largely in section, showing a complete apparatus or cyclic unit 75 adapted to carry out my new process. For simplicity of illustration, one hot stove only is shown as a part of the cycle; additional stoves are preferably provided, however, as shown in Fig. 2; Fig. 2 is a side view, partly 80 in section, of a group of stoves and the primary cracking chamber, with pipe connections, valves and temperature-controlling means; Fig. 3 is a cross-section on line III—III of Fig. 2 through one of the 85 stoves with plan view of the connecting pipes and operating valves; Fig. 4 is a vertical section of one of the gas-operated lift pumps employed for elevating the oil; Fig. 5 is a cross-section of the primary cracking chamber 90 taken immediately above the vapor inlet showing the vapor pipe for conducting thereto the vapors from the evaporating chambers; Fig. 6 is a vertical section through the evaporating units, with oil and 95 vapor pipes, oil level-regulating device and gas-pressure lift pumps, and Fig. 7 is a detail on a larger scale of the level-regulating device shown in Fig. 6.

Like reference characters indicate like 100 parts in the different views.

My invention involves apparatus constitut-

ing a cycle as follows: A brick-filled stove 1, a primary cracking chamber 2', secondary cracking chamber 2'', evaporator 3', evaporator 3'', reflux condensing column 4', rectifying column 4'', dephlegmating condenser 5, final condenser 6, gasoline accumulator tank 7, which is in gas pipe connection with compressor 44, which is in connection with the cold end of stove 1. The hot end of the 5 stove is in pipe connection with the primary cracking cylinder 2', and the succeeding parts mentioned above are in serial pipe connection, thus completing the cycle. My invention also includes means for producing a 10 separate vapor cycle, and comprises the connections 93 and 65 from the vapor chambers of the evaporators 3', 3'', to the upper chamber 64 in the primary cracking cylinder 2'. 15 In order that the invention may be clearly understood; the several parts of the apparatus above enumerated and others necessary to the performance of my invention will now be described in detail.

20 *Heating elements or stoves.*

Each of the stoves illustrated in Fig. 2 is preferably of the type known as a two-pass stove. Each stove is provided with a 25 valved burner inlet 47 through which liquid or gaseous fuel is admitted to the combustion chamber or hot end shown in stove 1''. A cold gas main 45 leads from the circulating compressor (hereinafter described) to the 30 stoves and a hot gas main 51 leads from the stoves to the top of the cracking chamber 2'. To heat the stoves, the valves 49 in the cold gas pipe 45 and the valves 50 in the hot gas main 51, are first closed to cut the 35 stove out of connection with the system, chimney valve 52 is opened and fuel and air are admitted through the inlet 47. Combustion takes place in chamber 48 and in the central flue 53, the flames pass upward to 40 the dome of the stove and thence downwardly through a multiplicity of vertical flues surrounding the central flue, as illustrated in the stove at the left of Fig. 2. Heat is imparted to the brick or other heat- 45 storage device and stored therein in this manner and the final products of combustion pass through the stack valve 52 to the chimney. In operation, one of the stoves is cut 50 into the system and employed to heat the 55 circulating gas and transmit heat to the cycle, while the remaining two stoves are cut out of the system and heated up, the time period for heating up thus being approximately twice that of the running period.

60 The method of operating the stoves consists in first charging a stove which has been heated up to its working temperature with oil gas or residue gas and bringing the gas pressure therein up to the working pressure 65 of the system. For example, when stove 1

is in operation in the system and stove 1' has been prepared to be cut in as above, valves 49 and 50 on stove 1' are opened and the circulating gas passes momentarily through both stoves 1 and 1', then the corresponding valves 49, 50, on stove 1 are closed. There is thus no interruption in the circulation of hot gas to and through the system. 70

Stove 1 having been cut out of the system, 75 it will be left full of gas under the pressure of the system, for example, 250 lbs. per square inch. At the cold end of each stove, a valved outlet pipe 54 Figure 2 is provided through which the gas stored in the stove 80 is now discharged into gas-holder tank 55, shown in Fig. 1 by means of a suitable conduit not shown, or to other point of storage or utilization. This leaves the gas in the stove at approximately atmospheric pressure. 85 This gas is now driven out or scavenged by injecting into the top of the stove a small amount of water through a pipe 56 connected with water under pressure.

The heat radiated from the brickwork 90 instantaneously converts the water into steam which drives out the remaining gas to the holder. Simultaneously with this scavenging operation and the closing of valve 56, the stack valve 52 is opened and burner 95 valve 47 is opened. Firing is then allowed to proceed until the stove is restored to the desired temperature condition.

In order to cut this stove into the system, the burner valve is closed and a small 100 amount of water is injected into the dome of the stove to scavenge the products of combustion into the chimney. The chimney valve is then closed and fuel oil or the heavy residue oil from the system, for example, 105 from the residue oil tank 14, is injected into the stove by means of pipe and valve 57, all of the other valves of the stove being closed. The oil entering the stove is cracked quickly 110 by the heat radiated from the brickwork and oil gas is generated. Oil is injected and cracked into oil gas until the pressure gauge 115 on the stove indicates the same pressure as that carried in the system itself. The stove is now in condition to be cut into the circulating system in the manner described above.

The length of time that a stove may be used to deliver heat to the system depends mainly on its size or heat storage capacity and the amount of gas passed through it. 120 During the period of blast or the time it is in use in the cycle, the temperature of the stove will gradually drop to a predetermined point, at which point the stove will be cut out. It is necessary and desirable that the temperature of the hot gas entering the cracking chamber 2' shall be uniform at all times. Means employed for maintaining such uniform gas temperature are shown in Fig. 2. 125

Temperature control means for cracking chambers.

I have shown in Figure 2 an extension or by-pass pipe 58 from the cold gas main 45 into the hot gas main 51, the by-pass preferably being provided with a valve 59. By this means, cold gas may be admixed with the hot gas from the stove to modify its temperature and to maintain a constant temperature in the top of the cracking chamber. This may be done by hand in connection with a pyrometer placed in the top of the hot gas main, as shown at 90, which affords an indication of the temperature therein, but I preferably interpose between the pyrometer and the valve, a pyrometer-controlled power mechanism by means of which the valve 59 is gradually moved as the temperature tends to change and more or less cold gas blended and admixed with the hot gas. This pyrometric-power control and valve is of a well known type and is indicated, generally, in Fig. 2 by the numeral 59^a. In this manner, the temperature of the gas entering the cracking chamber is maintained during the whole period of the run at a uniform point which does not fluctuate in practice more than 25° F. and may be controlled within a 10° range.

Cracking chambers.

The primary cracking chamber 2' is shown in Fig. 2 and the complete cracking unit 35 consisting of two chambers, 2' and 2'', is shown in Fig. 1. The primary cracking chamber 2' preferably consists of a vertical cylindrical steel shell connected near the top with hot gas main 51 with an outlet gas and vapor pipe 158 at the bottom connecting it with the bottom of the secondary cracking chamber 2''. The secondary cracking chamber 2'' is provided with an outlet gas and vapor pipe or conduit 68 at the top leading to evaporator 3'. These chambers 2' and 2'' are preferably lined with heat-resisting refractory walls 159 to prevent the loss of heat and to protect the steel shells. A metallic grid 61 is preferably placed above the bottom and above the outlet, which supports a column of special refractory shapes 60. These shapes, arranged in layers and staggered, have large surface area for spreading and filming the oil to be cracked and spiralled openings for the passage of the hot gases and to cause the hot gases to effectively contact with the films of oil. In the center of the primary cracking cylinder 2' is an extension of the duct pipe 62 from oil lift pump 13. This pipe is capped with a spray head or deflecting bonnet 63 which causes the oil as it emerges from 62 to be thrown downwardly over the top layer of the filling 60. Above the filling 60 there is a free space or chamber 64 into which the hot gas from the

stove, maintained at a uniform temperature by intermingling cold gas therewith, enters from hot gas main 51. The object of this gas chamber is to check the velocity of the gas and to cause it to spread and contact 70 evenly with the wet surfaces of the tile filling.

Vapors, mostly of intermediate boiling points, from the evaporators are conducted by vapor pipe 65 to the concentric distributing pipe 66, and blown or discharged through several spaced nozzles through apertures in the shell and lining into the gas chamber 64.

Chamber 2' is the primary cracking chamber of the system. As will be pointed out, large quantities of residual gas and hydrogen under pressure of the system, for example, 250 pounds per square inch, are heated to a uniform temperature and discharged into the chamber 64. The velocity of said gases is partly arrested and they descend evenly through the chamber and column of filling. Hot vapors are conducted from the recuperative part of the system after having been generated and trapped in the evaporators and are discharged into chamber 64, below the hot gas stream entering from 51. The hot gases and vapors commingle and the latter are heated to a desired cracking temperature 95 and the combined gases and vapors pass through the oil spray from the spray head 63, and pass downwardly through the filling 60 and impart heat to the thin films of oil on the large surfaces. The flow of oil from 100 the educt pipe 62 and spray head 63 is maintained preferably at such a rate as to keep the tile surfaces wet at all times. The volatile portions of the oil on the large surfaces are evaporated and the descending hot gases 105 and vapors commingle with the freshly generated vapors and impart the desired temperature to the latter and cause them to crack. The resulting vapors and heated gas pass out through conduit 158 into the bottom 110 of the secondary cracking chamber 2''.

The secondary cracking chamber 2'' is similar in regard to shape and refractory heat-insulating lining to 2' but its interior contains only the special tile filling 60, and gas-vapor spaces at top and bottom respectively. The purpose of this secondary cracking chamber is to retard and hold wet oil spray and mist mechanically carried by the gas stream and to thereby afford further 115 heating and cracking action. Another purpose served by this chamber is to more completely commingle the hot gases and vapors and to furnish space and time for recombination into saturated products.

The tile filling used in the cracking chambers and in the other vessels serves also as an efficient thermal stabilizer. When the system is under normal operating conditions, the heavy mass of the tile will have absorbed 130

heat and attained the working temperature of the various vessels. Any tendency to fluctuations in the temperatures, either above or below the established working temperatures at any point in the heat gradient from the cracking chambers to the rectifying column, are restricted by this large heat capacity in the refractory tile filling. Such filling gives out heat in case there is a drop in temperature and absorbs heat in case there should be an increase in temperature and acts as a temperature stabilizer at all times.

Evaporators.

Fig. 6 shows in detail the evaporators 3' and 3''. The evaporators consist of an outer steel shell 73', closed at the ends within which is placed a vertical boiler or heat exchanger 69, with tube heads and a multiplicity of tubes. Vapor pipe 68 from the secondary cracking chamber 2'' extends through the head of the outer shell of the evaporator 3' and connects with the upper head of tubular heat exchanger 69 in evaporator 3'. A similar pipe or conduit 70 extends from the bottom head of the heat exchanger 69 through the bottom head of the evaporator shell 73' and makes connection with a cross-over pipe 71. The second evaporator 3'' may be and is illustrated as of similar construction; cross-over pipe 71 connects by means of a pipe 70' with the lower head of the heat exchanger 69 in evaporator 3'' and pipe 72 from the head of this heat exchanger passes through the top of the evaporator 3'' and connects with the interior of reflux condensing column 4'. In other words, the hot gases and vapors leaving the secondary cracking chamber 2'' pass directly through pipe 68 into the space around the tubes of the heat exchanger 69 in evaporator 3' and are then conducted to the similar space around the tubes of the corresponding heat exchanger 69 in the second evaporator 3'', and thence are conducted by pipe 72 to the reflux condensing column 4'. The hot vapors and gases do not enter the interior space of the evaporator and do not come into direct contact with the oil therein. Oil is constantly pumped into the evaporators so as to maintain a constant level therein and to fill the tubes, the space below the tubes and a portion of the space above the tubes. The hot gases and vapors from the cracking chambers passing around the tubes thus impart their heat to the oil in the tubes.

In the upper portion of the evaporators is placed a column of tile filling 73. The main function of this filling is to spread the oil discharged into the evaporator by the lift pumps 11 and 12 out into thin films to allow of the rapid evaporation of vaporizable constituents. The temperature of the oil in evaporator 3'' is ordinarily about 600° F. and in evaporator 3' around 700° F., due to

the heat imparted to the oil in the rectifying column 4'', and reflux-condensing column 4', and to the heat transmitted by the hot gases and vapors from the cracking cylinders.

Fractions of intermediate boiling points refluxed in the dephlegmating condenser 5, rectifying column 4'', and reflux-condensing column 4', are discharged into the top of 75 3'' by lift pump 11 and flow in films over the hot tile filling. The remainder settles into the tubes of the heat exchanger and is heated to incipient cracking. The resulting vapors pass upward into vapor pipe 65. Likewise, the hot oil in 3'' is pumped by 80 lift pump 12 and discharged into the top of evaporator 3', flows over the hot tile surfaces in films, settles into the tubes and is subjected to a still higher temperature. The oil is further cracked and the evolved vapors 85 likewise pass upward into the vapor pipes 93 and 65. The vapor pressure in the evaporating space of the evaporators causes the vapors therefrom to pass through pipes 93, 93 to vapor pipe 65 (when the appropriate 90 valves are manipulated) and are thence discharged continuously into the top of the primary cracking chamber, as previously described.

Vapor pipe 65 from the vapor chambers 95 in the evaporators is extended by means of pipe 88 to connection with the cold gas main leading to the cold end of the stoves. By positioning and manipulating valve 86 on vapor pipe 65 and valve 87 on pipe 88, such 100 portion of the vapors from the evaporators 3' and 3'' as may be desired may be added to the gas stream 45 and passed into the operating stove. By completely closing valve 86 and fully opening valve 87, all the intermediate vapors from the evaporators can be passed through the stove and cracked therein instead of utilizing the method of passing the vapors through the cracking chamber 2'. This method is not the preferable one 110 but is effective and sometimes desirable.

In evaporators 3'' and 3', the liquid is maintained at a constant level 26 by means of a liquid-leveling device 106 which operates valve 28 in pipe 18'' through the connecting cable or chain 108. This preferred 115 level-regulating device indicated in Figs. 6 and 7 by numerals 105 to 108 is of well known construction and need not be described in detail other than to point out 120 that changes in level in the evaporators causes the element 106 (or a portion thereof) to expand or contract and this movement is multiplied and used to operate valves 28 and 40, as shown. It will be seen that oil 125 lifts 9, 10 and 11 are so positioned with regard to feed tanks 8', 8'', as to be at all times full of oil; likewise oil lifts 12 and 13 are so positioned with regard to oil level 130 26 in the evaporators as to be at all times

full of oil and oil will flow constantly into all of them by gravity.

The rate of pumping is maintained automatically in lift 11 by the level-regulating device 105—108 and valve 28 and is preferably adjusted by hand in lifts 9 and 10.

The flow of oil from evaporator 3" is through pipe 30. A similar pipe 31 in connection with pipe 30 allows a direct flow of oil from evaporator 3" to evaporator 3' for the purpose of insuring a level of oil in equilibrium in the two vessels whether the lift 12 is in operative condition or not. Another function served by pipes 30 and 31 is to allow oil to flow back into lift 12 and a forced rapid recirculation of the oil can thus be obtained so as to secure the advantages of rapid circulation of oil through the tubes and a greater or more efficient heat transfer. By means of pipe 32 connecting evaporator 3' to the bottom of lift 13, oil flows by gravity into the lift and is lifted by pressure gas to the top of cracking chamber 2' and sprayed over the tile surface therein. As this oil evaporates and more oil is pumped to maintain the flow over the surfaces, the oil level in the evaporators tends to fall and more oil is caused to flow into oil lift 11 and to be raised and discharged into evaporator 3", as required, by the operation of the level-regulating device 106 and valve 28.

Rectifying and condensing apparatus.

Reflux condensing column 4' is a vertical cylindrical steel shell filled with refractory tile in a similar manner to that previously described for the cracking chambers. The gas-vapor pipe 72 from evaporator 3" enters the top of condensing column 4' and is extended centrally therein to a space at the bottom underneath the filling. The gases and vapors are thereby conducted from the heat exchanger 69 in evaporator 3" and pass upwardly through the column of filling contacting with the oil flowing downwardly therethrough, which is being continuously pumped and discharged into the top by oil lift pump 10.

Rectifying column 4" is of similar general construction to 4'; that is, a vertical steel shell connected by pipe 74 with top of the reflux-condensing column 4' to conduct the gas and vapors therefrom and extended to the bottom of the filling so as to cause the gases and vapors to pass upwardly through the openings in the filling and contact with the films of oil flowing downwardly. Above the oil discharge point is an additional section of refractory filling 75 whose object is to retard and retain any mechanically carried rain or oil mist.

A dephlegmating or reflux condenser 5 is placed at a point preferably high enough to allow fractions condensed therein to run

back into rectifying column 4" by way of trap 77 and pipe connection 78. The gases and vapors are conducted from the top of rectifying column 4" by pipe 89 to dephlegmating condenser 5. The heavy ends condensed therein run, as described, back into column 4" and the gas and vapors of the desired product pass into a final condenser 6, thence into a suitable tank 7 in which the liquid product accumulates, allowing the residue gas to separate and pass to the circulating compressor 44 by means of pipe 76.

Circulating apparatus.

The oil lift pumps illustrated in detail in Fig. 4 are preferably operated by means of gas from the system. As reflux-condensing column 4' and rectifying column 4" are parts of the condensing system and as the gas used in these oil lifts passes directly to the water-cooled condensers, unheated gas is here employed. When the fresh oil in the system and the reflux oil reaches lift 11, it is above 350° F. and as the gas used in the evaporator lifts travels with the evolved vapors to the top of the primary cracking cylinder, I, therefore, preferably employ a tubular superheater 36 to heat the gas used in lift pumps 11, 12 and 13. In this manner, the oil heated by the countercurrent flow is not deprived of any of the heat it has picked up but additional heat is added to it. As the superheater is not a part of this invention, it will not be described in detail. It is heated preferably as shown by waste products of combustion from the stoves.

The operation of the oil lift pumps requires the use of gas under sufficient pressure above the pressure of the system to overcome the vertical head of oil in educt pipe 62. Compressor 44, which, it will be seen, is in the cycle, is employed to circulate residue gas from the condensers through the stove and chain of apparatus. The outgoing gas from this compressor 44 is at the highest pressure of the cycle. Pipe 46 conducts a portion of this gas to the inlet side of oil lift pump compressor 33. The work done by the compressor 33 is measured by the head of oil to be overcome in the oil lifts.

The oil lift pump gas from compressor 33 passes by means of pipes 34 and 38 to lifts 9 and 10. By closing valves 35' and 37' and opening valve 34', lifts 13, 12 and 11 may be operated through pipe connections 39', 39" and valve 40, cold gas being used and the superheater by-passed. It is preferable, however, to open valve 35' in pipe connection 35 to the superheater, open valve 37' and close 34'. Gas from gas main 34 then passes through the superheater and out through pipe 37 to pipe 39 and thence, as above, to lift pumps 13, 12 and 11.

The method of controlling the feed of oil to the evaporators by means of a level regulator 106 has been described above. The pivoted weighted lever 41 employed in this connection for operating the oil inlet valve 28 is also employed to operate the gas inlet valve 40 through connection 43. By suitable adjustment, it will be seen that pressure gas to lift pump 11 will be diminished 10 or entirely cut off simultaneously with the action of the oil valve 28 and will open in like manner as valve 28 opens, thus adjusting the gas flow to the oil feed requirement.

The purpose served by the continuous connecting pipes 18, 18', 18'' is to insure a steady uniform head of oil to all the lifts 9, 10 and 11 and to allow the leveling back of any excess of oil from the vessels 4'' and 4' into the feed tank. For example, if lift 9 20 should fail to operate, the oil flows without interruption into lift 10. Also, if lift 10 should be allowed to stop, the oil from the surfaces in 4' in excess of feed requirements will run by into feed tanks 8', 8''. In 25 other words, although the normal flow of oil is maintained by the lifts in the direction away from the feed tanks, any irregularities that might result from improper regulation or shut down of any part are 30 taken care of by the leveling action through pipes 18'', 18' and 18.

I do not confine myself to the use of gas-operated lift pumps, but may use reciprocating or other mechanical pumping devices 35 for elevating the oil.

Mode of operation.

In the preferred procedure, I may treat a heavy distillate from petroleum oil in order to produce therefrom lower boiling products, such as gasoline or motor spirits. To this end, the system having been placed under pressure in a manner to be more fully described, one of the oil feed tanks 8'' is 45 cut out of the system by closing the valve 15 in pipe 16, which connects its interior with the gas pressure of the system, closing valve 17 in oil feed pipe 18, relieving the pressure within tank 8'' by opening valve 21 in pipe 22 and opening valve 19 in feed pipe 20 which connects with an external supply of oil. Pipe 22 leads to residue gas tank 23 which is in direct connection with the inlet of the compressor 24 and with the residue 55 gas holder 55. Oil will now flow into feed tank 8'' by suction or gravity or may be forced in by means of a pump in line 20. By restoring valves 15 and 17 to their original positions, feed tanks 8'' and 8' will 60 both be under the pressure of the system by means of the connection through pipe 16 and both will will be in liquid connection with the oil lift pump 9. The oil feed tanks 8', 8'' are now in operative connection with the 65 system and oil will flow into the oil lifts 9,

10 and 11 by gravity through pipe 18 and its extensions 18' and 18''.

The oil is forced by means of oil lift pump 9 into the upper part of rectifying column 4'' and is discharged on the top layer of the 70 main column of filling. This oil, together with the condensate from dephlegmating or reflux condenser 5, meets the vapors and gases from reflux-condensing column 4' admitted by pipe 74, these vapors and gases 75 passing in the reverse direction to the incoming oil. The oil flowing downwardly over the surfaces in countercurrent direction to the ascending gases and vapors is colder than the latter and, therefore, condenses out therefrom vapor constituents 80 heavier than the desired final product. These condensed heavy fractions flow downwardly with the fresh oil through leg 25 into pipe 18' to lift pump 10, which forces 85 it through pipe 100 into reflux-condensing column 4''. As in the case of column 4'', the oil mingles with gases and vapors of a higher temperature (the latter having been used to heat oil in the evaporators 3', 3'') 90 and a similar action takes place, the oil becoming hotter and its volume augmented by the condensing and refluxing of the intermediate boiling point vapors in the gas or vapor stream. From reflux-condensing 95 column 4', the oil passing through pipe 25' and valve 28 is forced by lift pump 11 into the top portion of evaporator 3'' where the checkerwork produces further vaporization. The level of oil in the two evaporators is 100 maintained constant at a point slightly above the tubes 69, as has been described.

Here the oil is heated and vaporized by the hot vapors and gases from the reaction chamber which pass in heat exchange relationship to the oil in tubes 69 and under the conditions obtaining in the evaporators the oil is heated to incipient cracking.

The oil from evaporators 3' and 3'' now 110 at a temperature around 700° F., depending upon the character of the hydrocarbon treated and under the pressure prevailing in the system, usually in the neighborhood of 250 pounds per square inch, passes through pipe 32 into oil lift 13 by means of which it is 115 forced into the reaction chamber, preferably in the form of a spray, as shown, and flows over the extended tile surfaces in thin films.

Previous to this, a stove in the system has been heated up. Gases from the system as, 120 for example, from residue gas tank 55, or hydrocarbon gases from an external source, if desired, are forced by means of compressor 24 and compressor 44 into the stove through pipe 45. The temperature of the 125 stove is sufficient to impart to the gases an average temperature in the neighborhood of 1400° F. in order that the heat-bearing gases may maintain in the reaction chamber 2', a temperature between 1150 to 1200° F. which, 130

in general, has been found to be the preferable temperature range. It will be understood, however, that time as well as temperature is a factor in the cracking of oils so that if a very high temperature is to be employed then the time factor must be very short and vice versa.

In order that the temperature in reaction chamber 2' may not rise above a predetermined point and that the gases and vapors from the stoves may be supplied at a uniform temperature, relatively cold gas from pipe 45 is by-passed into the conduit 51 leading from the stove to the reaction chamber whenever the temperature of the gases in conduit 51 becomes excessive, the quantity of gas by-passed being controlled by temperature-regulated valve 59 in by-pass 58, as has been described.

It will now be seen that hot oil is caused to pass over greatly extended surfaces in the reaction chamber and is in a most favorable condition, for the action of the hot gases and vapors from the stove maintained at the optimum temperature and pressure. The gases from the stove contain a large proportion of hydrogen and, due to the favorable reaction conditions maintained in the chamber, the formation of unsaturated compounds can be minimized.

The vapors evolved in the evaporators, being as a rule too heavy for use as motor spirit, are normally led through pipes 93 and 65 into the reaction chamber. Thus the petroleum entering the reaction chamber has been separated into two portions; that which could be vaporized under the conditions obtaining in the evaporating system is admitted as such at 64, whereas the liquid portion admitted flows in thin films over greatly extended surfaces, both portions thus being in the most favorable condition for cracking.

In case it is desired to replenish the supply of fixed gases in the system, a portion, or the whole of the vapors produced in evaporators 3' and 3'', may be admitted to pipe 45 by manipulating valves 86 and 87.

The liquid residue from chambers 2' and 2'' is allowed to pass into the sump 14 through pipe 14' whence it may be recirculated by means of lift 13 and pipe 14'', or may be drawn off to a point of storage or utilization by means of valve 141 at the bottom.

The vapors and gases from reaction chamber 2' now pass into chamber 2'' where additional extended surfaces are presented. The function of the secondary cracking chamber has already been described. The hot products from the secondary reaction chamber 2'' pass around tubes 69 in evaporators 3' and 3'' and afford the heating means therefor. The condensate from the gas and vapor stream refluxed in the heating spaces of the

evaporators 3' and 3'' flows out through pipe 92 into lift pump 11 whence it is returned to the vapor space of the evaporator 3''.

The vapors and gases having yielded a portion of their heat in the evaporators pass therefrom through 72 into the reflux-condensing column 4' and thence into rectifying column 4'', as has been described. The uncondensed portions then pass through reflux condenser 5, and condenser 6, the condensate being collected in tank 7. This condensate represents the final liquid product of the system.

As shown above, the vapors in the gas-vapor stream from the primary cracking chamber 2', in passing through the train of apparatus toward the final condenser 6, pass through a descending scale of temperatures produced by the counter flow of the colder oil toward the cracking chamber. A large portion of the vapors generated in cracking chamber 2' are heavier in boiling point than the desired product and these heavier vapors are condensed by the lowered temperatures, join the oil stream and are continuously returned to the interior of the evaporators. In the evaporators such portions of the refluxed fractions thus returned from the dephlegmating condenser 5, rectifying column 4'', and reflux-condensing column 4', together with lower-boiling point fractions produced by the cracking of oil in the heat-exchangers, are to a large extent vaporized and are caused to pass by virtue of their vapor pressure through pipe connections 93, 65, into the top of the primary cracking chamber. In this manner not only is the sensible heat of the vapors and gases conserved but also the latent heat of condensation. An important function and advantage of the system, however, is the continuous condensing out of vapors heavier than the desired product and the continuous return of these fractions to and through the cracking chamber.

The conditions of temperature, pressure and atmosphere in the cracking chamber are maintained at the most effective points for producing a maximum conversion into the desired product.

Although I have found that in this process the amount of oil broken down into fixed gases is inconsiderable, there is sufficient gas formation to maintain pressure in the system autogenously. To regulate the pressure and prevent the accumulation of pressure above the desired point, an outlet 83 and weighted back-pressure valve 84 are provided on the accumulator tank 7. The excess residue gas that may be thus discharged enters gas-receiving tank 23, whence any liquid condensate that may be separated out is removed through valved connection 85. The residue gas entering tank 23 passes by

way of pipes 79 and 80 to gas holder storage tank 55, which is also in connection with the "plenum" compressor 24 by means of pipe 81.

5 The gas pressure in the cycle or system is built up and maintained in two ways, either one or both of which may be employed. The most suitable working pressure may be taken as 250 pounds per square inch. It 10 will be understood that this pressure is essentially that of the carrier gas, and that the partial pressures of the vapors of the liquid in the cracking chamber are only a small fraction thereof. The pressure will be 15 greatest in the stove and cracking cylinder and less in the subsequent units on account of the frictional resistance of the gas passing through the system and lowest in accumulator tank 7. The weighted back-pressure 20 valve 84 is set to the right point of pressure so as to allow of the escape of any excess of gas. If the pressure of the plant has been discharged or allowed to become much lowered below the working pressure, 25 oil is injected into the stove through valved connection 57 and cracked into oil gas until the pressure is restored. Any fluctuations in pressure are automatically cared for in a similar manner by connecting an oil storage 30 tank directly with inlet 57 and maintaining a gas pressure on the oil equal to that of the system by a gas-pressure balancing pipe. If, for any reason, the pressure in the system is allowed to drop, oil will flow through 35 57 automatically, and by virtue of cracking to oil gas, restore the pressure condition. For small fluctuations, however, a small compressor 24, which I have termed a "plenum" 40 compressor, is provided which receives gas by direct connection with the floating gas-holder residue tank 55 and forces gas into the cycle, discharging the gas into the cold gas main 45. This plenum compressor 24 is caused to operate by connection, not shown, 45 with the pressure of the cycle. If the pressure in the cycle drops below the desired pressure, compressor 24 by the automatic closing of a valve in the by-pass 82, draws gas from the storage holder 55 and forces it 50 into the cold gas main 45. By means of these two methods, though either method can be used independently, the pressure of the system can be maintained with a minimum variation independent of the temperature.

55 It will be understood that the hydrocarbon gases passing through the hot blast stoves will be subjected to severe cracking and that their composition will tend to approach a mixture of hydrogen and methane 60 of varying proportions. In general, this will be true regardless of the composition of the hydrocarbon material passed through the stoves. The function of these gases is not only to supply heat to accomplish conversion of the hydrocarbons, but is consid-

ered to form a so-called protective atmosphere which will have the effect of inhibiting the formation of fixed gases from the cracking reaction and thus throw the equilibrium in the direction of the product desired, as for example gasoline. By the expression "hydrogen containing gases" it is meant to include, either singly or collectively hydrogen per se as well as methane and similar gaseous hydrocarbons of neutral 75 character.

I claim:

1. The process of producing hydrocarbon compounds, which consists in feeding a liquid hydrocarbon into a chamber, heating 80 said liquid hydrocarbon while in said chamber by contacting heated hydrogen containing gases therewith, subjecting the hydrocarbon coming into said chamber to a preliminary partial fractional distillation by 85 thermally contacting the heated gases and vapors from said chamber therewith and passing the vapors and gases from said fractional distillation directly into said chamber.

2. The process of producing hydrocarbon 90 compounds which consists in feeding a liquid hydrocarbon into a chamber, heating said liquid hydrocarbon while in said chamber by contacting heated hydrogen containing gases from a heating element therewith, 95 subjecting the hydrocarbon coming into said chamber to a preliminary partial fractional distillation by thermally contacting the heated gases and vapors from said chamber therewith and passing a portion of said 100 vapors to said heating element and a portion to said chamber.

3. The process of producing hydrocarbon compounds, which consists in feeding a liquid hydrocarbon into a chamber, heating said 105 liquid hydrocarbon while in said chamber by contacting heated cracked hydrocarbon gases and vapors therewith, subjecting the hydrocarbon coming into said chamber to a preliminary partial fractional distillation 110 by thermally contacting the heated gases and vapors from said chamber therewith, passing the vapors and gases from said fractional distillation directly into said chamber and subjecting uncondensed vapors and 115 gases from the chamber to condensation conditions, heating the uncondensed vapors and gases and utilizing them to convert additional quantities of said hydrocarbon.

4. The process of producing hydrocarbon 120 compounds, which consists in feeding a liquid hydrocarbon into a chamber, heating said liquid hydrocarbon while in said chamber by contacting heated cracked hydrocarbon gases and vapors from a heating element 125 therewith, subjecting the hydrocarbon coming into said chamber to a preliminary partial fractional distillation by thermally contacting the heated gases and vapors from said chamber therewith, passing a portion of 130

said vapors to said heating element, a portion to said chamber and subjecting uncondensed vapors and gases from the chamber to condensation conditions and returning 5 uncondensed vapors and gases to the heating element.

5. The process of producing hydrocarbon compounds, which consists in feeding a liquid hydrocarbon into a chamber, heating 10 said liquid hydrocarbon while in said chamber by contacting heated hydrogen containing gases therewith under mechanically maintained pressure of said gases, said gases being heated to a temperature sufficient to 15 evolve vapor from said hydrocarbon, subjecting the hydrocarbon coming into said chamber to a preliminary partial fractional distillation by thermally contacting the heated gases and vapors from said chamber 20 therewith and passing the vapors and gases from said fractional distillation directly into said chamber.

6. The process of producing hydrocarbon compounds, which consists in feeding hydro- 25 carbon liquid and hydrocarbon vapor into a chamber, heating said liquid and vapor hydrocarbon while in said chamber by contacting and commingling heated hydrogen containing gases therewith of sufficient vol- 30 ume and heat units to accomplish conversion of said hydrocarbon, subjecting the liquid hydrocarbon coming into said chamber to a partial fractional distillation by utilizing the heated gases and vapors from said chamber 35 as a heating means therefor, subjecting the incoming hydrocarbon liquid at a point more remote than the said fractional distillation point to physical contact with said gases and vapors and subjecting the uncondensed gases and vapors to condensation 40 conditions.

7. The process of producing hydrocarbon compounds, which comprises evolving hydrocarbon vapors from hydrocarbon liquid, sub- 45 jecting a portion of said vapor to heat, contacting said heated vapor and gases produced therefrom with liquid hydrocarbon in a confined space, whereby other hydrocarbons are produced and admitting to said confined 50 space a portion of said first evolved hydrocarbon vapor.

8. The process of producing hydrocarbon compounds, which comprises evolving hydrocarbon vapors from hydrocarbon liquid, 55 subjecting a portion of said vapors to heat and pressure, contacting said heated vapor and gases produced therefrom with liquid hydrocarbon in a confined space under mechanically maintained pressure of said vapor 60 and gases, said vapor and gas being heated to a temperature sufficient to evolve vapor from said hydrocarbon liquid, whereby other hydrocarbons are produced and admitting to said confined space a portion of said first 65 evolved hydrocarbon vapor.

9. In an apparatus for treating hydrocarbon oils, a heating element, a reaction chamber, means for feeding hot vapors and gases from said heating element to said reaction chamber, means for feeding gas and vapor 70 to said heating element, means for conducting the products from said reaction chamber in heat exchange relationship to incoming oil, whereby a portion thereof is vaporized, and means of conducting vapor so produced 75 by said heat exchange to said heating element or said reaction chamber as desired.

10. In an apparatus for treating hydrocarbon oils, a heating element, a reaction chamber, means for feeding hot vapors and 80 gases from said heating element to said reaction chamber, means for feeding gas and vapor to said heating element, means for conducting the products from said reaction chamber in heat exchange relationship to 85 incoming oil, whereby a portion thereof is vaporized, means for conducting vapor so produced to said heating element or said reaction chamber as desired, and temperature-controlled means for admitting cooler vapors 90 or gases to the reaction chamber to maintain a uniform temperature in said reaction chamber.

11. In an apparatus for treating hydrocarbon oils, a heating element, a reaction 95 chamber, means for feeding hot vapors and gases from said heating element to said reaction chamber, a source of gases or vapors, means for feeding gas and vapor to said heating element, means for conducting the 100 products from said reaction chamber in heat exchange relationship to incoming oil, whereby a portion thereof is vaporized, and temperature-controlled means for admitting relatively cold vapors or gases from said 105 source to the stream of hot gases fed to said reaction chamber to maintain a uniform temperature in said reaction chamber.

12. In an apparatus for treating hydrocarbon oils, a heating element, a reaction 110 chamber, means for feeding hot vapors and gases from said heating element to said reaction chamber, means for feeding gas and vapor to said heating element, means for conducting the products from said reaction 115 chamber in heat exchange relationship to incoming oil, whereby a portion thereof is vaporized, means for conducting vapor so produced to said heating element or said reaction chamber as desired, and means to compress a portion of the gas and vapor so produced and to subject the system to the resulting pressure.

13. In an apparatus for treating hydrocarbon oils, a heating element, a reaction 120 chamber, means for feeding hot vapors and gases from said heating element to said reaction chamber, means for feeding gas and vapor to said heating element, means for conducting the products from said reaction 125 chamber in heat exchange relationship to incoming oil, whereby a portion thereof is vaporized, means for conducting vapor so produced to said heating element or said reaction chamber as desired, and means to compress a portion of the gas and vapor so produced and to subject the system to the resulting pressure.

- chamber in heat exchange relationship to incoming oil, whereby a portion thereof is vaporized, means to compress a portion of the gas and vapor so produced and to subject the system to the resulting pressure, and means for circulating the liquid hydro carbon by means of gas or vapor, the pressure of which has been increased above that in the system.
14. In an apparatus for treating hydrocarbon oils, a heating element, a reaction chamber, means for feeding hot vapors and gases from said heating element to said reaction chamber, means for feeding gas and vapor to said heating element, means for conducting the products from said reaction chamber in heat exchange relationship to incoming oil, whereby a portion thereof is vaporized, gas-lift pumps for circulating the liquid hydrocarbons, a compressor for circulating gas or vapor throughout the system, a compressor for maintaining the required pressure in the system, a source of gas or vapor supply for said compressor last mentioned and a compressor for furnishing gas at a pressure sufficient to operate said lift pumps.
15. In an apparatus for treating hydrocarbon oils, a heating element, a reaction chamber, means for feeding hot vapors and gases from said heating element to said reaction chamber, means for feeding gas and vapor to said heating element, means for conducting the products from said reaction chamber in heat exchange relationship to incoming oil, whereby a portion thereof is vaporized, means to compress a portion of the gas and vapor so produced and to subject the system to the resulting pressure, means for circulating the liquid hydrocarbon by means of gas or vapor, the pressure of which has been increased above that in the system, and means for heating said gas or vapor for operating said liquid-circulating means.
16. In an apparatus for treating hydrocarbon oils, a heating element, a reaction chamber, means for feeding hot vapors and gases from said heating element to said reaction chamber, means for feeding gas and vapor to said heating element, an evaporator, means for conducting the products from said reaction chamber through the heating space of said evaporator, means in the vapor space of said evaporator affording extended contact surfaces, means for flowing liquid hydrocarbon over said surfaces, means for collecting condensate from the heating space of the evaporator and means for returning said condensate to the vapor space of the evaporator.
17. In an apparatus for treating hydrocarbon oils, a heating element, a reaction chamber, means for feeding hot vapors and gases from said heating element to said reaction chamber, means for feeding gas and

vapor to said heating element, an evaporator, means for conducting the products from said reaction chamber through the heating space of said evaporator, and means to admit the vapor produced in said evaporator to said reaction chamber.

18. The process of producing hydrocarbon compounds from liquid hydrocarbon and hydrocarbon gas and vapor, which consists in feeding the liquid through a heat exchange unit into a reaction chamber and over extended surfaces therein, compressing hydrocarbon-bearing gas and vapor to maintain pressure conditions within the system independent of the temperature conditions, propelling said gas and vapor through a heating device to heat the same and crack the vapor therein, passing the thus heated gas and cracked vapor into the reaction chamber to contact directly with the liquid therein, employing the resulting vapor and gas to evolve additional vapor from the liquid in the heat exchange unit, passing the thus derived vapor into the reaction chamber, continuing this action in a cyclic manner, and subjecting said resulting vapor to condensation to separate out the desired product.

19. The process of producing hydrocarbon compounds from liquid hydrocarbon and hydrocarbon gas and vapor, which consists in feeding the liquid through a heat exchange unit into a reaction chamber compressing hydrocarbon-bearing gas and vapor to maintain pressure conditions within the system independent of the temperature conditions and propelling said gas and vapor through a heating device to heat the same and crack the vapor therein, passing the thus heated gas and cracked vapor into the reaction chamber to contact directly with the liquid therein, employing the resulting vapor and gas to evolve additional vapor from the liquid in the heat exchange unit, passing the thus derived vapor into the reaction chamber, continuing this action in a cyclic manner, subjecting said resulting vapor to condensation to separate out the desired product, and compressing the remaining gas and vapor and propelling the same again through the system in a cyclic manner.

20. In an apparatus for treating hydrocarbons, a reaction chamber, means for subjecting hydrocarbons therein to cracking conditions, an evaporator comprising a vapor and liquid space and a heating space, extended contact surfaces in said vapor space, means for admitting heated fluid to the heating space of said evaporator, means for flowing hydrocarbon oil over said extended surfaces, and means for admitting the thus heated oil into the said reaction chamber and means admitting vapor from said evaporating space to said reaction chamber.

21. In an apparatus for treating hydro-

carbons, a reaction chamber, means for subjecting hydrocarbons therein to cracking conditions, an evaporator comprising a vapor and liquid space and a heating space closed 5 from said vapor and liquid space, checker-work in said vapor space, means for admitting heated fluid to the heating space of said evaporator, means for spraying liquid hydrocarbon over said checker-work, and 10 means for admitting the thus heated oil into the reaction chamber.

22. In an apparatus for treating hydrocarbons, a reaction chamber, means for subjecting hydrocarbons therein to cracking 15 conditions, an evaporator comprising a vapor and liquid space and a heating space, extended contact surfaces in said vapor space, means for admitting heated fluid into the heating space of said evaporator, means including pumping means for flowing hydrocarbon oil over said extended surfaces, means 20 for recirculating liquid from said vapor and liquid space over said extended surfaces, and means for admitting the thus heated oil to 25 the reaction chamber.

23. In an apparatus for treating hydrocarbons, a reaction chamber, means for subjecting hydrocarbons therein to cracking conditions, an evaporator comprising a vapor 30 and liquid space and a heating space, extended contact surfaces in said vapor space, means for admitting hot products from said reaction chamber into the heating space of said evaporator, means for flowing hydro- 35 carbon oil over said extended contact surfaces, means for adding the material condensed in said heating space to liquid undergoing evaporation and for circulating the combined liquids over said extended surfaces, and means for admitting the thus heated oil to the reaction chamber.

24. The process of treating hydrocarbon compounds to obtain other hydrocarbon compounds therefrom, which consists in introducing 45 into a chamber petroleum compounds to be converted, heating up a mass of heat absorbing material until said material is at the requisite temperature, transferring, by means of gases, the heat from 50 said material to said hydrocarbons in said closed chamber to accomplish the conversion thereof, subjecting the said hydrocarbon coming into said chamber to a preliminary partial fractional distillation by thermally 55 contacting the heated gases and vapors from said chamber therewith, and passing the vapors and gases from said fractional distillation directly into said chamber.

25. The process of producing hydrocarbon 60 compounds, which consists in feeding a hydrocarbon fluid to be cracked into a chamber, heating said hydrocarbon while in said chamber by contacting and commingling heated gases therewith of sufficient thermal 65 content and temperature to accomplish con-

version of the said hydrocarbon, subjecting the said hydrocarbon coming into said chamber to a preliminary partial fractional distillation by thermally contacting the heated gases and vapors from said chamber therewith, and passing the vapors and gases from said fractional distillation directly into said chamber.

26. The process of producing hydrocarbon compounds which consists in feeding a hydrocarbon fluid to be cracked into a chamber, heating said hydrocarbon while in said chamber by contacting and commingling heated hydrogen containing gases therewith of sufficient thermal content and temperature 70 to accomplish conversion of the said hydrocarbon, subjecting the said hydrocarbon coming into said chamber to a preliminary partial fractional distillation by thermally contacting the heated gases and 75 vapors from said chamber therewith, and passing the vapors and gases from said fractional distillation directly into said chamber.

27. The process of producing hydrocarbon 80 compounds which consists in feeding a hydrocarbon fluid to be cracked into a chamber, heating said hydrocarbon while in said chamber by contacting and commingling heated, cracked hydrocarbon gases and 85 vapors therewith of sufficient thermal content and temperature to accomplish conversion of the said hydrocarbon, subjecting the said hydrocarbon coming into said chamber to a preliminary partial fractional distillation 90 by thermally contacting the heated gases and vapors from said chamber therewith, and passing the vapors and gases from said fractional distillation directly into said chamber, subjecting uncondensed vapors and 95 gases from the chamber to condensing conditions, heating the uncondensed vapors and gases and utilizing them to convert additional quantities of said hydrocarbon.

28. The process of treating hydrocarbon 100 compounds which consists in heating hydrocarbon liquid and evolving vapors therefrom at one point, feeding the heated hydrocarbon liquid and evolved vapor into a chamber at a second point, converting said 110 hydrocarbon liquid and evolved hydrocarbon vapor in said chamber by contacting and commingling therewith gas heated in a heating element at a third point and employing said heated gas and dissociated vapor to heat 115 liquid and evolve further vapors at the first point.

29. The process of producing hydrocarbon 120 compounds, which consists in feeding hydrocarbon liquid and hydrocarbon vapor into a chamber, contacting and commingling therewith gas, heated to a temperature sufficient to convert said hydrocarbons in said chamber, employing the said gas and dissociated vapors to fractionally distill the in- 125

coming liquid hydrocarbon at a point beyond said chamber, passing the vapors and gases from said fractional distillation directly into said chamber, and subjecting the 5 incoming hydrocarbon liquid at a point more remote than the said fractional distillation point to physical contact with said gases and vapors.

30. The process of producing hydrocarbon 10 compounds which consists in evolving hydrocarbon vapor from hydrocarbon liquid, heating a gaseous fluid of hydrocarbon nature from a separate source to above the cracking temperature, supplementing said 15 fluid undergoing heating by adding thereto a portion of said vapor, admitting said heated mixture and a portion of said first evolved vapor to a confined space containing liquid hydrocarbon and mechanically maintaining 20 pressure of the vapor and gases at a desirable value, said gaseous heated mixture having been heated to a temperature sufficient to evolve vapor from said hydrocarbon liquid thereby other hydrocarbons are produced. 25

31. In the process of treating petroleum 30 oils to convert them into compounds suitable as motor fuels, the steps which consist in introducing into a chamber petroleum compounds to be converted, heating up a mass 35 of inert, refractory, heat absorbing material until said material is above the temperature required for the conversion reaction, passing a heat-carrier gas thereover whereby to heat said gas to above such conversion temperature, introducing the thus heated gas into said chamber and there physically mingling same with the petroleum compounds therein, controlling the temperature 40 of the reacting compounds whereby the conversion of said petroleum compounds is brought about under substantially uniform temperature conditions, the products from said reaction chamber containing the vapors 45 of the desired compounds of the process in addition to the carrier gas, and subjecting said products from said chamber to conditions producing liquefaction of said compounds suitable as motor fuels. 50

51. 32. In the process of heating petroleum 55 oils to convert them into compounds suitable as motor fuels, the steps which consist in introducing into a chamber petroleum compounds to be converted, heating up a mass 60 of inert, refractory, heat absorbing material until said material is above the temperature required for the conversion reaction, passing a heat-carrier gas thereover whereby to heat said gas to above such conversion temperature, introducing the thus heated gas into said chamber and there physically mingling same with the petroleum 65 therein, said gas being of sufficient quantity and heat units as to furnish substantially the entire heat necessary for the con-

version reaction, controlling the temperature of the reacting compounds whereby the conversion of said petroleum compounds is brought about under substantially uniform temperature conditions, the products from 70 said reaction chamber containing the vapors of the desired compounds of the process in addition to the added carrier gas, and subjecting the products from said chamber to conditions producing liquefaction of said 75 compounds suitable as motor fuels.

33. In the process of treating petroleum oils to convert them into compounds of lower molecular weight suitable as motor fuels, the steps which consist in introducing 80 into a chamber petroleum compounds to be converted, heating up a mass of inert, refractory, heat absorbing material until said material is above that temperature required for the conversion reaction, passing a heat 85 carrier gas thereover whereby to heat said gas to above such conversion temperature, introducing the thus heated gas into said chamber and there physically mingling same with the petroleum compounds therein, controlling the temperature of the reacting 90 compounds whereby the conversion of said petroleum compounds is brought about under substantially uniform temperature conditions, the products from said reaction chamber containing the vapors of the desired 95 compounds of the process in addition to the carrier gas, and subjecting said products from said chamber to conditions producing liquefaction of said compounds suitable as 100 motor fuels with the separation of residual gas and using said residual gas to constitute in part at least the carrier gas.

34. In the process of treating petroleum 105 oils to convert them into compounds suitable as motor fuels, the steps which consist in introducing into a chamber petroleum compounds to be converted, heating up a mass of inert, refractory, heat absorbing material 110 until said material is above the temperature required for the conversion reaction, passing a hydrogen-containing, heat-carrier gas thereover whereby to heat said gas to above such conversion temperature, introducing said heated gas into said chamber wherein it is physically mingled with the petroleum 115 compounds undergoing conversion therein, controlling the temperature of said reacting compounds whereby the conversion of said petroleum compounds is brought about under substantially uniform conditions, the products from said reaction chamber containing the vapors of the desired compounds of the process in addition to the carrier gas, and subjecting the products from said chamber to conditions producing liquefaction of 120 said compounds suitable as motor fuels. 125

35. In the process of treating hydrocarbon 130 compounds to convert same into compounds suitable as motor fuels, the steps

which consist in introducing into a chamber hydrocarbon material to be converted, heating up a mass of inert, refractory, heat absorbing material until said material is above the temperature required for the conversion reaction, passing a heat carrier gas thereover whereby to heat said gas to above such conversion temperature, maintaining said gas at a substantially uniform temperature above the conversion temperature as said mass cools down, and then introducing said mixture into said chamber and there physically mingling same with the hydrocarbon therein whereby the conversion of said hydrocarbon is brought about under substantially uniform temperature conditions, the products from said reaction chamber containing the vapors of the desired compounds of the process in addition to the carrier gas, and subjecting the products from said chamber to conditions producing liquefaction of said compounds suitable as motor fuels.

36. In the process of treating hydrocarbon compounds to convert same into compounds of lower molecular weight suitable as motor fuels, the steps which consist in introducing into a chamber hydrocarbon material to be converted, heating up a mass of inert, refractory, heat absorbing material until said material is above the temperature required for the conversion reaction, passing a heat carrier gas thereover whereby to heat said gas to above such conversion temperature, adding a varying quantity of relatively cold gas to said heated gas as said mass cools down whereby the produced mixture is maintained at a substantially uniform temperature above the conversion temperature, and then introducing said mixture into said chamber and there physically mingling same with the hydrocarbon therein whereby the conversion of said hydrocarbon is brought about under substantially uniform temperature conditions, the products from said reaction chamber containing the vapors of the desired compounds of the process in addition to the carrier gas, and subjecting the products from said chamber to conditions producing liquefaction of said compounds suitable as motor fuels.

37. In the process of treating petroleum oils to convert them into compounds of lower molecular weight suitable as motor fuels, the steps which consist in continuously introducing into a chamber petroleum compounds to be converted, heating up a mass of inert, refractory, heat absorbing material until it is above the temperature required for the conversion reaction, passing a heat carrier gas thereover whereby to heat said gas to above such conversion temperature, and then introducing the heated gas from said refractory material into said closed

chamber physically to mingle with said petroleum therein to accomplish the conversion thereof, controlling the temperature of said reacting compounds whereby the conversion of said petroleum compounds is brought about under substantially uniform conditions, heating up a second mass of inert, refractory, heat absorbing material until it is above said temperature required for the conversion reaction, continuing said gas heating step until said refractory mass first mentioned has cooled off, cutting off the supply of carrier gas thereto, then heating carrier gas by means of said second heated refractory mass, and introducing the so heated gas into said reaction chamber under continued controlled temperature conditions therein, thus continuing the operation of gas heating by means of successive units of heated refractory material whereby a continuous supply of heated carrier gas is produced and said conversion process is substantially continuous.

38. In the process of treating petroleum oils to convert them into compounds suitable as motor fuels, the steps which consist in introducing into a chamber petroleum compounds to be converted, heating up a mass of inert, refractory, heat absorbing material in a chamber separate from said chamber first mentioned, until said material is above the temperature required for the conversion reaction, passing a heat-carrier gas thereover whereby to heat said gas to above such conversion temperature, utilizing the thus heated gas to accomplish the conversion of said compounds under substantially uniform temperature conditions by introducing same into said chamber and there physically mingling same with the petroleum compounds therein, the products from said reaction chamber containing the vapors of the desired compounds of the process in addition to the carrier gas, and subjecting the products from said chamber to conditions producing liquefaction of said compounds suitable as motor fuels.

39. In an apparatus of the character described, a regenerative heating element, means for burning fuel to heat same, means for feeding relatively cold, heat-carrier gas to said element, a reaction chamber separate from said heating element, means for admitting hydrocarbon compounds into said reaction chamber which are to be subjected to the action of the heated carrier gas, means for maintaining temperature conditions in said chamber substantially uniform, means for admitting the carrier gas heated in said regenerative heating element to said reaction chamber, means affording vapor liquefaction conditions, and means joining said liquefaction means with said reaction chamber whereby to recover a desired product

from said reaction chamber after the reaction has taken place.

40. In an apparatus of the character described, a regenerative heating element, means for burning fuel to heat same, means for feeding relatively cold heat-carrier gas to said element, a reaction chamber separate from said heating element, and comprising a refractory-lined chamber, means for admitting hydrocarbon compounds into said reaction chamber which are to be subjected to the action of heated carrier gas, means for maintaining temperature conditions in said chamber substantially uniform, means 5 for admitting the carrier gas heated in said regenerative heater to said reaction chamber, means affording vapor liquefaction conditions, and means joining said liquefaction means with said reaction chamber whereby 15 to recover a desired product from said reaction chamber after the reaction has taken place.

41. The process of producing hydrocarbon compounds of lower molecular weight from hydrocarbon liquid by cracking which 25 consists in heating up a mass of inert, heat retaining material until said material is at the requisite temperature, separately vaporizing the hydrocarbon to be cracked without substantial cracking thereof, passing a hydrogen containing gas over said mass of heated inert material, introducing the vapor produced by the evaporating step mentioned 30 into contact with the thus heated hydrogen containing gas, said gas being of such thermal quality both as to temperature and heat units as to accomplish substantially the entire cracking reaction and constituting substantially the sole source of heat for said 35 reaction and subjecting the vapor and gas products of the reaction to condensing conditions.

42. The process of producing gasoline-like compounds from petroleum liquid by cracking, which consists in heating up a mass of inert, heat-retaining material, until said material is at the requisite temperature, separately vaporizing the hydrocarbons to be cracked without substantial cracking thereof, 45 passing hydrogen-containing gas over said mass of heated inert material whereby the said gas attains a temperature in excess of that required for cracking, adding a diminishing quantity of relatively cold gas to said heated gas as said mass cools down thereby maintaining the temperature of the mixture substantially uniform, introducing the vapor produced by the evaporating step mentioned 50 into contact with the thus heated hydrogen

containing gas, said gas mixture being of 60 such thermal quality both as to temperature and heat units as to accomplish substantially the entire cracking reaction and constituting the sole source of heat for said reaction, and subjecting the vapor and gas products 65 of the reaction to condensing conditions.

43. In the process of treating petroleum oils to convert them into compounds suitable as motor fuels, the steps which consist in storing up heat in a gaseous heat-carrier until 70 the same is at least the conversion temperature, admitting said heated gas to a reaction zone, subjecting the oil to vaporizing conditions without substantial cracking thereof in a vaporizing zone distinct from said reaction 75 zone, separating the produced vapor from the unvaporized liquid, mingling said vapor and said heated carrier-gas in said reaction zone to bring about conversion of said vapor, controlling the temperature of the reacting 80 compounds whereby the conversion of said petroleum vapor is brought about under substantially uniform temperature conditions, said carrier-gas being of such quantity and heat units as to furnish the entire heat necessary 85 to convert said vapor so mingled therewith, and subjecting the mixture of the converted vapor and carrier-gas to conditions producing liquefaction of said compounds suitable as motor fuels. 90

44. In the process of treating petroleum oils to convert them into compounds suitable as motor fuels, the steps which consist in storing up heat in a gaseous heat-carrier until the same is above the conversion temperature, admitting said heated gas to a reaction zone, subjecting the oil to vaporizing conditions without substantial cracking thereof in a vaporizing zone distinct from said reaction zone, separating the produced 95 vapor from the unvaporized liquid, mingling said vapor and said heated carrier-gas in said reaction zone to bring about conversion of said vapor, controlling the temperature of the reacting compounds whereby the conversion of said petroleum vapor is brought about under such temperature conditions that a converted product is had which is of a composition suitable as a motor fuel, said carrier-gas being of such quantity and heat 100 units as to furnish the entire heat necessary to convert said vapor so mingled therewith, and subjecting the mixture of the converted vapor and carrier-gas to conditions producing liquefaction of said compounds suitable 105 as motor fuels. 110

WILLIAM JOHN KNOX.
